COMBINED THREAD HOLDER AND CUTTER

Application filed April 28, 1930. Serial No. 447,873.

This invention relates to thread holders for weft replenishing looms and it is the general object of the invention to provide a device of this kind with a weft cutter to remove excess thread so that the holder may function properly to tension the weft ends.

In multicolor weft replenishing mechanisms it is customary to arrange the reserve bobbins in several vertical stacks. The weft ends from the bobbins are held by some form of thread holder which preferably is movable to take up slack as it occurs in the threads. One form of thread holder employs a spring between the coils of which weft is held. These holders move downwardly by gravity in guides and I have found that the latter are likely to become clogged with the weft ends and impede the downward motion of the thread holder. It is accordingly an important object of my present invention to provide a thread cutter which shall be so placed as to effect removal of any excess weft which may be drawn off by the weaver when new bobbins are inserted in the magazine.

It is a further object of my invention to provide threaded gripping springs which are operable from points below the cutter, so that the threads will be free to move to any raised spring and still be in the bight between the cutting edges.

With these and other objects in view which will appear as the description proceeds my invention resides in the combination and arrangement of parts hereinafter described and set forth in the claims.

In the accompanying drawings, wherein a convenient embodiment of my invention is set forth,

Fig. 1 is a front elevation of a portion of a magazine having my improved thread holder and cutter applied thereto,

Fig. 2 is a side elevation on an enlarged scale taken in the direction of arrow 2, Fig. 1,

Fig. 3 is a vertical section taken on line 3-3 of Fig. 2 with one of the weights shown in low position,

Fig. 4 is a top plan view on an enlarged scale taken in the direction of arrow 4, Fig. 1,

Fig. 5 is a view similar to a portion of

Fig. 3 but with the cutter blades separated, and

Fig. 6 is a detail vertical section through one of the weighted members showing the manner of holding the several parts together by means of the coil spring.

The magazine 10 is arranged in known manner to support a plurality of vertical stacks of reserve bobbins which may be of different colors or characteristics. Weft ends 60 W extend from these bobbins and are attached to the form of thread holder forming the subject matter of my present invention. The magazine comprises in its construction tie rods 11 which may be extended to the 65 left as shown in Fig. 1 to provide a supporting means for holding a guide frame 12. The latter, as shown in Figs. 3 and 4, is provided in this instance with four separate vertical preferably cylindrical holes 13 which extend 70 throughout the height of the frame.

In each hole 13 there is a weighted element 14 having a head 15 into which is driven the upper end of a push rod 16. The head has a reduced neck 17 frictionally gripped by the 75 upper coils of a normally closed tension spring 18. The lower end of said spring is frictionally held to a second neck 19 formed on the upper end of a weight 20 having therethrough a bore 21 to receive the lower 80 end of the rod 16.

The wires of which the springs are formed have horizontal fingers 22 passing through slots 23 which extend from the corresponding holes 13 through the left hand vertical 85 face of the frame 12 as viewed in Figs. 3 and 4. The slots 23 do not extend to the bottom of the frame 12 but stop as indicated at 25 to define rests for the fingers 22 of the wires, thereby providing supports for the weighted 90 elements 14.

The upper end of the slots 23 have extending thereacross retaining plate 26 held to the frame by screws 27. This plate may be perforated to receive the tie rods 11 and has secured to the lower edge thereof a stationary cutter blade 28 held in position by screws 29. This blade has an upwardly extending cutting edge 30 as shown in Fig. 5 to cooperate with a movable cutter blade 31 piv- 100

oted on one of the tie rods, as shown in Fig. 2. The pivoted cutter blade is held frictionally in position by a collar 32 prevented from having longitudinal movement along tie rod 11 by set screw 33. An extension 34 of the cutter blade 31 may be employed to engage a part of the fixed structure to limit angular movement of said blade.

When it is desired to add bobbins of any selected slack the pivoted cutter blade will be raised to the dot and dash line position in Fig. 2, which position it will retain due to the friction of collar 32. The proper rod 16 will then be raised to cause engagement between blade 26 and the moving finger 22, and continued upward movement of the rod will expand the coils of the corresponding spring. The operator may then pass the ends of the newly inserted bobbins under the cutter blade 31 and between the coils of the spring. The rod 16 is sufficiently long so that the finger 22 will engage the bottom of the plate 26 before upward movement of the rod is prevented by the bottom of the frame 12. The operator will then release the rod 16 and it, together with the movable parts associated therewith, will fall to tension the threads. Thereafter the operator will depress the blade 31 to cut off such excess thread as extends beyond the cutter and is not necessary to the correct functioning of the weights. In this way a very short amount of weft extends beyond the slack taking up weight and there will be practically no clogging of the holes 13 or slots 23.

As the several springs and weights fall to take up slack, the weft ends will slide over a guide rib 40 projecting above the top 41 of the frame 12 to facilitate their movement toward the weights.

From the foregoing it will be seen that I have provided means to remove excess length of weft ends projecting beyond the thread holder and slack taking up devices. A part at least of the cutting mechanism is carried by the thread holding unit so that the same length of weft remains irrespective of the position of the frame 12 along the tie rods. Furthermore, the springs are expanded by applying a force below the pivoted blade 31, so that the weft ends may be placed under the said blade without interference with the holders. Also, the slots 23 are so placed as to receive the short weft ends remaining after the cutting operation, thereby preventing the ends from entering the holes 13. The slots 23 cooperate with the fingers 22 to guide the movable thread holders to prevent rotation thereof in the holes 13.

Having thus described my invention it will be seen that changes and modifications may be made therein by those skilled in the art without departing from the spirit and scope of the invention and I do not wish to be

limited to the details herein disclosed, but what I claim is:

1. In a weft replenishing mechanism operating with a plurality of reserve weft bobbins from which extend weft ends, a thread holder for the weft ends, and a thread cutter located beyond the holder with respect to the bobbins and positioned to sever excess length of weft ends extending from the reserve bobbins. 75

2. In a weft replenishing mechanism operating with a plurality of reserve weft bobbins from which extend weft ends, a thread holder for the weft ends, and a thread cutter positioned to sever excess length of weft ends of 80 the reserve bobbins extending to the holder.

3. In a weft replenishing mechanism operating with a plurality of reserve weft bobbins from which extend weft ends, a fixed support, a thread holder on the support, and a thread cutter mounted on the support and positioned to sever excess length of weft ends extending from the reserve bobbins beyond the thread holder. 85

4. In a weft replenishing mechanism operating with a plurality of reserve weft bobbins from which extend weft ends, a fixed stand, a thread holder movable on the stand, and a thread cutter positioned to sever excess length of weft ends extending from the reserve bobbins beyond the holder with reference to the bobbins. 90

5. In a loom, a magazine to support reserve bobbins from which extend weft ends, a thread cutter positioned to sever excess length 100 of weft ends extending from the reserve bobbins, and a thread holder located between the cutter and magazine and attached to the weft ends.

6. In a weft replenishing loom having reserve supplies of weft from which extend weft ends, a movable thread holder, a frame in which the holder moves, and a thread cutter adjacent the holder positioned to sever excess length of weft ends extending from 110 the reserve bobbins to prevent the ends from entering the frame and interfering with the movement of the holder. 106

7. In a weft replenishing loom having reserve supplies of weft from which extend weft ends, a support having a guideway therein, a thread holder movable in the guideway and connected to the weft ends, and a cutter to sever excess length of weft ends to prevent the latter from entering the guideway. 115

8. In a weft replenishing loom having reserve supplies of weft from which extend weft ends, a fixed frame having a guideway therein, a thread holder movable in the guideway to take up slack in the weft ends, and a cutter adjacent the guideway to sever excess length of weft ends extending beyond the thread holder from the bobbins. 125

9. In a weft replenishing mechanism oper- 130

ating with a plurality of weft bobbins arranged in a plurality of stacks and from which weft ends extend, a plurality of movable thread holders to take up slack in the weft ends, a thread cutter to sever excess length of weft ends, and manual means for operating any of the thread holders from a point beneath the thread cutter.

10. In a weft replenishing loom having reserve supplies of weft from which extend weft ends, a fixed frame to be held at different distances from the bobbins, a thread holder carried by the frame and attached to the weft ends, and a cutting member carried by the frame and movable therewith to assist in severing excess weft ends.

11. In a loom, a magazine to support reserve bobbins from which extend weft ends, a thread cutter to sever excess length of weft ends, a thread holder located between the cutter and magazine and attached to the weft ends, and friction means to hold the cutter open to receive weft ends.

12. In a weft replenishing loom having reserve supplies of weft from which extend weft ends, a fixed frame having a guideway therein, a thread holder movable in the guideway and attached to the weft ends, a guide finger on the holder, the frame having a slot for the finger, and a cutter to sever excess length of weft ends, the holder being between the cutter and bobbins and the slot extending toward the cutter and positioned to receive the short weft end between the cutter and holder.

In testimony whereof I have hereunto affixed my signature.

ALBERT A. GORDON.
